DESIGN FOR A DISPLAY RACK FOR BREAD OR SIMILAR ARTICLE

Ernest R. Erickson, Des Moines, Iowa, assignor to
C. E. Erickson Company, Incorporated, Des Moines, Iowa, a corporation of Iowa

Application January 22, 1937, Serial No. 67,213

Term of patent 7 years

To all whom it may concern:

Be it known that I, Ernest R. Erickson, a citizen of the United States and a resident of Des Moines, in the county of Polk and State of Iowa, have invented a new, original, and ornamental Design for a Display Rack for Bread or Similar Article, of which the following is a specification, reference being had to the accompanying drawing, forming part hereof.

for bread or similar article illustrating my design.

I claim:

The ornamental design for a display rack for bread or similar article substantially as shown.

ERNEST R. ERICKSON.
